US00D983218S

(12) **United States Design Patent** (10) **Patent No.:** **US D983,218 S**
Coverstone et al. (45) **Date of Patent:** **** Apr. 11, 2023**

(54) **DISPLAY SCREEN OR PORTION THEREOF WITH GRAPHICAL USER INTERFACE**

(71) **Applicant:** **STAR CO Scientific Technologies Advanced Research Co, LLC,**
Longview, TX (US)

(72) **Inventors:** **Thomas E. Coverstone**, Longview, TX (US); **Jason Montgomery**, Longview, TX (US); **Taylor Buscher**, Longview, TX (US); **Azrael Maxcy-Brown**, Longview, TX (US); **Rachel Pollard**, Longview, TX (US)

(73) **Assignee:** **STAR CO SCIENTIFIC TECHNOLOGIES ADVANCED RESEARCH CO DIRECT.COM, L.L.C.**, Longview, TX (US)

(**) **Term:** **15 Years**

(21) **Appl. No.:** **29/703,454**

(22) **Filed:** **Aug. 27, 2019**

(74) **Attorney, Agent, or Firm:** McAndrews Held & Malloy, Ltd.

(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The outer perimeter shown in evenly-spaced dashed broken lines in the figures depicts a display screen or portion thereof and forms no part of the claimed design. The remaining dashed broken lines in the figures depict portions of the graphical user interface that form no part of the claimed design.

1 Claim, 2 Drawing Sheets
